COMBINATION VIBRATOR AND MIXER

Arthur O. Braatz, Racine, Wis.

Application February 8, 1950, Serial No. 142,971

5 Claims. (Cl. 259—131)

1

This invention relates to improvements in a combination vibrator and mixer.

Dentists, jewelers, and others often find it necessary, in the course of their work to prepare relatively small quantities of plaster, silicates, or other investment materials. While mixing the ingredients for the plastic mass, a considerable amount of air is entrained in the form of relatively small bubbles. In order to produce a sound casting, it is necessary to eliminate these bubbles before the mass is placed in a mold, and it is important that all steps be performed quickly before the plastic material has had an opportunity to set.

It has been common practice in the past for dentists, in preparing plaster, to mix the ingredients by hand in a rubber cup or bowl. After the plastic mass has been properly mixed, the cup and its contents have been vibrated either by hand or by the use of a mechanical vibrating device. The vibrating devices heretofore placed on the market for this purpose have been relatively expensive, and their high cost, considered with the fact that these devices are designed to perform a single operation only, has prevented these devices from coming into common use. Furthermore, these prior devices have imparted only a vertical up and down movement to the cup.

With the above in mind, it is a general object of the present invention to provide a combination mixing and vibrating device.

A further object of the invention is to provide an improved device of the class described which is relatively inexpensive.

A further object of the invention is to provide a device of the class described which is adapted for convenient use in association with a rubber cup or bowl of the type ordinarily used by dentists in mixing plaster ingredients.

A further object of the invention is to provide a device of the class described comprising an electric hand mixer having a pair of spaced rotatable shafts provided at their ends with mixing elements, said shafts also being provided intermediate their length with eccentric vibrator portions.

A further object of the invention is to provide a device of the class described wherein the shaft portions between the mixing elements and the motor housing are long enough to permit the bottom of a mixing cup to be placed on and vibrated by the eccentric members when the shafts are disposed horizontally, so that the vibration may be performed immediately after mixing.

A further object of the invention is to provide a device of the class described which is strong and

2

durable, which is relatively simple in construction and easily cleaned, and which is otherwise well adapted for the purposes described.

With the above and other objects in view, the invention consists of the improved hand mixer, and all of its parts and combinations, as set forth in the claims, and all equivalents thereof.

In the drawing accompanying and forming a part of this specification, wherein are shown two 10 embodiments of the invention, and wherein like characters of reference indicate the same parts in all of the views:

Fig. 1 is a side elevational view of a preferred form of the improved mixer showing it disposed 15 in proper position to mix a quantity of plastic material in a rubber cup of the type commonly used by dentists, a part of said cup being broken away and shown in section;

Fig. 2 is an end view of the mixer of Fig. 1 removed from the cup;

Fig. 3 is a side view of the preferred form of the improved mixer showing the shafts thereof held in a horizontal plane and showing the rubber cup and its plastic ingredients positioned on the 25 eccentric portions of said shafts in a manner to be vibrated thereby when said shafts are rotated;

Fig. 4 is a fragmentary side view of a modified form of the invention wherein the eccentric portions of the shafts are formed by integral offsets 30 therein; and

Fig. 5 is a sectional view taken approximately on the line 5—5 of Fig. 3 showing the novel vibrating action.

Referring more particularly to the drawing, the 35 numeral 10 indicates an electrically driven hand mixer of any suitable type having an elongated body 11 of generally round cross-sectional shape, said body having built therein an electric driving motor and suitable drive gearing as is well known in the art. A two-wire electrical conductor 12 projects from one end of the body 11 and is provided with a suitable male plug (not shown) for connection with an electrical outlet. The operation of the mixer 10 is controlled by an electrical switch 13 which is movable axially of the body 11 to turn the motor on and off.

Projecting from the end portion of the body 11 which is opposite the end from which the conductor 12 projects, and disposed at substantially 50 a right angle with respect to the longitudinal axis of the body 11, are a pair of spaced parallel shafts 14 and 15. The shafts 14 and 15 are rotated in opposite directions at the same speed by the electric motor within the body 11 through the before-mentioned conventional drive gearing

(not shown). At the outer end of each of the shafts 14 and 15 is a looped mixing element 16. The element 16 on the shaft 14 is preferably positioned at a right angle with respect to the element 16 of the shaft 15, and said elements are preferably of such size that they may be simultaneously accommodated in the conventional dentist's plaster mixing cup 20.

Fixed to each of the shafts 14 and 15 in a position substantially midway of the distance between the mixing elements 16 and the body 11 is a cam member 17. As shown in the drawing, each of the cam members 17 has two diametrically oppositely disposed high points, as indicated in Figs. 1 to 3 by the numeral 18 which refers to the cam 17 on the shaft 15 and by the numerals 19 which refers to the cam on the shaft 14. Cams 17 are angularly offset from one another as shown in Figs. 1 to 3, for a purpose which will be pointed out hereinafter.

In operation, the ingredients of a batch of plaster may be placed in a rubber cup 20, of the type commonly used by dentists, and said ingredients are then thoroughly mixed by introducing the mixing elements 16 into said ingredients, as shown in Fig. 1, and causing said mixing members to be rotated by the driving motor. The thorough mixing resulting from the use of the mixing elements 16 causes a considerable amount of air to be entrained in the plastic mass in the form of bubbles, and said air must be eliminated before the mixture is used.

To remove the bubbles from the plastic mass in the cup 20, the mixer 10 may be immediately turned to the position shown in Fig. 3, and the cup 20 is preferably manually held with its bottom in contact with the cams 17, as also shown in said figure. By causing the shafts 14 and 15, as well as the cams 17 to be rotated while in the position of Fig. 3, the high points 18 and 19 of the cams 17 impinge upon the bottom of the cup 20 and cause said cup to be thoroughly vibrated. Since the cams 17 are offset from one another and since the cams are rotating outwardly in reverse directions, the bottom of the cup on one side will be engaged first by one of the cams to tilt that side of the cup upwardly, and the cup in a somewhat tilted position will be moved upwardly and transversely outwardly. The opposite side of the cup will then be engaged by one of the high points on the other cam to tilt the cup in a reverse direction and move it upwardly and transversely outwardly in a direction opposite to its first direction of movement. This action is shown in Fig. 5. This vibration causes the air entrained in the plastic mass within the cup 20 to be rapidly expelled therefrom, and after the air is expelled by this method, the plastic mass is ready for use in the conventional manner.

It is an important feature of the invention that the shafts of 14 and 15 be of sufficient length that any conventional size cup 20 may be accommodated by the improved device in the manner shown in Fig. 3.

Fig. 4 shows an alternative construction of the improved mixer wherein the body is indicated by the numeral 10', and the shafts are indicated by the numerals 14' and 15'. In place of the cams 17, the shafts 14' and 15' are formed with eccentric offsets 17' which serve the same purpose and operate in substantially the same manner as the cams 17 of the preferred form. It will be noted that the offset 17' of the shaft 14' is preferably displaced approximately 180° from the offset 17' of the shaft 15'.

It is apparent that the improved mixer provides, in a single device, means for mechanically mixing plastic materials as well as means for conveniently vibrating the plastic materials immediately after they have been thoroughly mixed. Thus, there is no substantial time interval between mixing and vibrating and there is no chance for the mass to prematurely set. This inexpensive device eliminates the need for expensive mixing or vibrating equipment, and it also reduces the amount of equipment necessary in an office or laboratory while at the same time increasing the efficiency.

The improved device is simple in construction, compact, and easily cleaned.

Various changes and modifications may be made without departing from the spirit of the invention, and all of such changes are contemplated, as may come within the scope of the claims.

What I claim is:

1. A combination vibrator and mixer, comprising: a body; at least one rotatable shaft projecting from said body; means in said body for rotating said shaft; a mixing element on said shaft adjacent the projecting end thereof, said element being of such size that it may be accommodated in a mixing cup, and said shaft having a portion of substantial length between the body and said mixing element; and at least one eccentric member on said shaft portion intermediate the mixing element and said body, said eccentric member being adapted to serve as a vibrator when a mixing cup is positioned in contact therewith during rotation of the shaft.

2. A combination vibrator and mixer, comprising: a body; a pair of spaced, parallel, rotatable shafts projecting from said body; means in said body for rotating said shafts; a mixing element on each of said shafts adjacent the projecting end thereof, said elements being of such size and so positioned that they may be simultaneously accommodated in a mixing cup, and said shafts each having a portion of substantial length between the body and said mixing elements; and an eccentric member fixed on each of said shaft portions intermediate the mixing element and said body, said eccentric being adapted to serve as vibrators when a mixing cup is positioned in contact therewith during rotation of the shaft.

3. A combination vibrator and mixer, comprising: a body; a pair of spaced, parallel, rotatable shafts projecting from said body; means in said body for rotating said shafts simultaneously at the same speed; a mixing element on each of said shafts adjacent the projecting end thereof, said elements being of such size and so positioned that they may be simultaneously accommodated in a mixing cup, and said shafts each having a portion of substantial length between the body and said mixing elements; and an eccentric member fixed on each of said shaft portions intermediate the mixing element and said body, the eccentric of one shaft being angularly offset from the eccentric of the shaft, and said eccentric being adapted to serve as vibrators when a mixing cup is positioned in contact therewith during rotation of the shaft.

4. A combination vibrator and mixer, comprising: a body; a pair of spaced parallel rotatable shafts projecting from said body; means in said body for rotating said shafts simultaneously at the same speeds; a mixing element on each of said shafts adjacent the projecting end thereof, said elements being of such size and so positioned

that they may be simultaneously accommodated in a mixing cup, and said shafts each having a portion of substantial length between the body and said mixing elements; and an eccentric member fixed on each of said shaft portions intermediate the mixing element and said body, said eccentric members each having a pair of diametrically oppositely disposed offset portions, and the eccentric member of one shaft being angularly offset from the eccentric member of the other shaft, and said eccentric members being adapted to serve as vibrators when a mixing cup is positioned in contact therewith during rotation of the shaft.

5. A combination vibrator and mixer, comprising: a body; a pair of spaced parallel rotatable shafts projecting from said body; means in said body for rotating said shafts simultaneously at the same speed; a mixing element on each of said shafts adjacent the projecting end thereof, said elements being of such size and so positioned that they may be simultaneously accommodated in a mixing cup, and said shafts each having a portion of substantial length between the body and said mixing elements; and an eccentric offset

10

5

formed in each of said shaft portions intermediate the mixing element and said body, the eccentric offset in one shaft being angularly disposed with respect to the offset in the other shaft, and said offsets being adapted to serve as vibrators when a mixing cup is positioned in contact therewith during rotation of the shaft.
